UNITED STATES PATENT OFFICE.

DAVID C. PATTERSON, OF OMAHA, NEBRASKA.

BUILDING CONSTRUCTION.

1,349,850.

Specification of Letters Patent. Patented Aug. 17, 1920.

Application filed September 18, 1919. Serial No. 324,467.

To all whom it may concern:

Be it known that I, DAVID C. PATTERSON, a citizen of the United States, residing at Omaha, in the county of Douglas and State 5 of Nebraska, have invented certain new and useful Improvements in Building Construction, of which the following is a specification.

This invention relates to an improvement 10 in building construction and has for its principal object to provide a confined air space for the outer walls of a building, to exclude the cold or heat or dampness from the interior. Another object is to provide 15 such a construction that buildings may be built conveniently and economically. The invention is fully illustrated in an accompanying drawing, and the novel and useful features are described hereinafter and are 20 particularly pointed out in the appended claim. In the drawing, Figure 1 is a broken away view in section showing one of the walls of the building and an abutting basement floor. Fig. 2 is a view in side elevation 25 showing a part of the upright wall, the stucco therefor being omitted.

Referring now to the drawing for a more particular description, I provide two-part side walls 3, each having an air-space 4 continuous from its footing 5 to the upper floor joist 6 the height of these walls depending upon the number of stories required for a building.

Each upright side wall consists of an 35 outer part *a* and an inner part *b*, preferably constructed of cement or similar adhesive material and connected by tie-rods 7, said rods having angular terminals embedded in a manner to maintain the parts *a* and *b* in 40 spaced relation and approximately parallel; and for convenience when building the walls these parts are formed as rectangular blocks with channels therebetween, as shown in the drawing.

The footing 5 may be constructed of concrete or any other material adapted to sustain the weight of the side walls, and as described, said walls are imperforate with the exception that suitable openings are provided for doors 8 and windows 9, hair-cloth 50 or other compressible insulating material being employed and interposed between the wall and the frames 11 of the doors and windows, so that air within the spaces will 55 not communicate with the atmosphere, caps 12 of concrete or wood together with hair-

cloth or other suitable insulating material 13 being employed for effecting a closure of the top of the wall 3. Numerals 14 indicate headers for the floor-joist 6, and at 15 is indicated hair-cloth or similar fibrous insulating material interposed between the floor-joist 6 and the floor 16 thereon, the lower side of the floor-joist 6 being provided with insulating material 17 and plaster 18. 60 65

As best shown in Fig. 1, that part below the first floor-joist 19 is for a basement, and since a part thereof is generally disposed below the ground line and generally is subject to dampness, a double wall, preferably constructed of concrete, is provided for its floor, 70 consisting of a floor-base 20 and a floor-plate 21 sustained above the base by a plurality of spacing-bars 22, whereby an air-space *c* is provided having a length and breadth 75 corresponding to the area, in plan, of the basement, said air-space not being in communication with the atmosphere, said double floor preferably consisting of rectangular sections *d*, for convenience, the bars 22 80 being of such proportion that they will sustain the weight incidental to the uses of the floor 21, and the angular terminals of said bars being embedded in the concrete or cement when the sections are formed. 85

Numerals 23 indicate plaster which is applied to the interior of the side walls, and at 24 as indicated stucco for parts of the side walls above the ground line.

The construction is considered to be simple, and dwelling houses or larger buildings 90 may be conveniently built in the manner described; and since the interior of the building is practically surrounded by a confined air-space, the expense for heating during extreme cold weather will be reduced to a minimum, and the interior of the building 95 will remain comfortably cool during hot weather, dampness for the basement being practically eliminated.

What I claim as new and desire to secure 100 by Letters Patent is:—

In building construction, a pair of upright walls each being provided with an opening, tie-rods embedded in said walls for 105 maintaining them approximately parallel and to provide an air space therebetween, a frame in the openings of said walls, a footing for supporting and for closing the air space at the bottom of said walls, an insulating element mounted upon the upper terminals of said walls, a cap-member upon said 110

insulating element, a compressible fibrous element in the openings of said walls for engaging the frame, a base-member of adhesive material extending horizontally from the footing, upright spacing-bars embedded in and projecting above the base-member, and a plurality of floor-plates of adhesive material disposed end to end above the base-member engaging the spacing-bars for pro-

viding an air-space between the base-member and floor-plates approximately equal in area to the area of said base-member. 10

In testimony whereof I have affixed my signature in presence of two witnesses.

DAVID C. PATTERSON.
